INVENTOR

William M. Scott

BY
Cornelia S. Ellet
his ATTORNEY

UNITED STATES PATENT OFFICE.

WILLIAM M. SCOTT, OF TREDYFFRIN TOWNSHIP, CHESTER COUNTY, PENNSYLVANIA.

SWITCH-HOUSING STRUCTURE.

Original application filed October 2, 1919, Serial No. 328,056. Divided and this application filed May 22, 1920. Serial No. 383,362.

To all whom it may concern:

Be it known that I, WILLIAM M. SCOTT, a citizen of the United States, residing in Tredyffrin Township, in the county of 5 Chester and State of Pennsylvania, have invented a new and useful Switch-Housing Structure, of which the following is a specification.

My invention relates to structure for 10 mounting and housing electric switches, circuit breakers and kindred protective devices.

It is the object of my invention to provide switching or automatic circuit breaker 15 mechanism, or the like, mounted upon a suitable support or base, together with a housing, of which said base or support may be one wall, into and from which extend the supply and consumption circuit 20 conductors; it is a further object of my invention to provide structure of the character referred to in which the housing is a support for the switch base or support, for the switching or circuit breaker mechanism 25 carried thereby, and for any other structure carried by such switch base or support; and it is a further object of my invention to provide with structure of the character referred to a second housing for 30 the switching or circuit breaking mechanism carried by the base or support for the switching or circuit breaker mechanism.

To these ends I have devised structure 35 of the character hereinafter described, and one of many forms of which is illustrated in the accompanying drawings, in which:

Fig. 1 is a side elevational view of structure embodying my invention, a wall of each 40 of the housings being in part removed for the sake of clearness.

Fig. 2 is a front elevational view of the structure shown in Fig. 1, the front wall of the second housing being in part removed.

Referring to the drawings, 13 is a base 45 or support, preferably of slate or other suitable insulating material, upon one side of which is mounted the switching mechanism which, in the example illustrated, 50 is an automatic circuit breaker mechanism comprising two switching mechanisms or switch arms A and B, disposed side by side upon the base 13; it is to be understood, however, that my in-

vention is not limited to the particular 55 character of the switching or circuit breaker mechanism, and is in no way limited to the number of arms or switching mechanisms employed. In the example illustrated, the two switch arms are substantially 60 similar in structure, and therefore a description of one will suffice for the other, the parts in the arm B corresponding to those in the arm A having reference characters similar to those in the arm A 65 with the addition of prime marks.

Referring to arm A, it comprises the main upper and lower terminal blocks 1 and 2, normally engaged and bridged by the movable laminated contact member 3 70 carried by the arm 21, the latter carrying also the movable shunt carbon contact 4 co-operating with the stationary shunt carbon contact 5.

The laminated bridging member 3 is carried 75 by the arm 21 pivoted at 22 upon a bracket secured to the base 13. The arm 21 is operated by a toggle comprising the link 23 pivoted to the base at 24 and at 26 to the link member 25, which in turn is 80 pivoted at 27 to the aforesaid arm 21. The toggle structure thus formed holds the bridging member 3 in circuit closing position indicated, and is held in such position by the latch 6 engaging the pin or roller 7 carried by the toggle member 25, and pivoted to a back bracket secured upon base 13. Upon the pin 29 carried by member 25 is a roller 30.

The main terminals 1 and 1' are respectively 90 secured upon the base 13 by the studs 19 and 19' extending through the base to the rear thereof.

The stud 20 extends from the rear of the base 13 through the same and connects with 95 one terminal of the winding or coil of the electro-magnet 32 whose other terminal connects by conductor 32a, Fig. 2, with the lower main terminal 2 of the breaker arm A. The lower main terminal 2' of the 100 breaker arm B is secured to the base 13 by the stud 20' extending through the base to the rear thereof.

At the rear is the housing 11, preferably 105 of sheet steel, which is adapted to be secured, as by screws 12, 12, to any supporting structure, as a pillar, beam or the like. To the housing 11 is secured the base 13,

the housing 11 then serving, if desired, as the support for the base 13 and the parts carried thereby, including the switching mechanism and the second housing herein-
5 after referred to. The base 13 may be supported upon or secured to the housing 11 by screws *a* extending through the base from the front thereof and engaging in members or brackets *b* secured to the housing 11.

Through opposite side or end walls 11^a and 11^b of the housing 11 extend conduits 15 and 15', respectively. Upon the threaded end of each of these conduits are the 15 nuts 18 and 18', between which are clamped the aforesaid end walls 11^a and 11^b.

Within the conduit 15 are disposed the insulated conductors 16 and 16', as of a supply circuit, these conductors extending 20 beyond the conduit 15 into the interior of the housing 11 and ending in terminals such as 16^a, secured to the aforesaid studs 19 and 19', as by nuts 16^b.

To the studs 20 and 20' are similarly secured by nuts 20^b and terminals 20^a upon the ends of the insulated conductors 17 and 17', these conductors entering and extending through the conduit 15' to the consumption circuit.

30 It will accordingly be understood that, in the example illustrated, the circuit through the arm A is from conductor 16, through stud 19, upper terminal block 1, bridging member 3, lower terminal block 35 2, through the winding of the electro-magnet 32, to stud 20 and thence to one side of the consumption circuit through the conductor 17; and the circuit through the arm B is from the other supply circuit conductor 16', through stud 19', to the upper terminal 1' through the bridging member 3' to the lower terminal block 2' through the stud 20' and conductor 17' to the other side of the consumption circuit.

40 45 Co-operating with the electro-magnet 32 is the pivoted armature 33, to which is secured the transversely extending bar 8 having at its ends the members 9 and 9' adapted to cause actuation of the restraining latches of the switch arms A and B, when the magnet 32 is energized by excessive current flowing through the structure described.

55 Secured to the base 13, as by screws *c* engaging in brackets *d*, and enclosing or housing the circuit breaker mechanism described, is the housing H, preferably of sheet steel, having the door 37, pivoted at 57^a. The door may be locked closed by a padlock 74 or the like engaging in the hook end 69 of the arm 70 carried by and pivoted upon the door 37. Through the staple 68 carried by the housing H extends the hook end 69 of the member 70.

60 65 Pivoted upon and carried by the door 37

is the member 46, having the operator's handle 43, and carrying the pin 57 which may be embraced by a padlock 59 extending through the staple 58 carried by the door 37, so as to prevent operation of the member 46. 70 On the inner side of the door 37 the member 46 carries the arms 39 and 40, upon which are pivoted, respectively, the rollers 41 and 42 adapted to engage the rollers 30 and 30' of the different switch arms to actuate them 75 to circuit closing position in succession. A spring 56 attached at one end to the door 37 and at its other end at 55 to the member 46 returns the member 46 to neutral or central position.

80 Carried by the door 37 is the push button 34 adapted to actuate the push rod 35, which in turn actuates the pivoted member 36, which actuates the armature 33 for manually tripping the circuit breaker mechanism.

85 The structure described therefore comprises a base carrying switching mechanism or the like secured to a housing on the opposite side thereof from the switching mechanism, with connections to the switching mechanism through the base and within the housing to conductors extending into or through conduit structure communicating with or secured to the housing. 90

95 The structure described comprises further two housings, one of them enclosing switching mechanism or the like on one side of a base, the base being common to both housings, and connections with the switching mechanism being established in a second housing through conductors disposed in conduit structure or the like. 100

105 By structure of the character described complete protection is afforded not only to the switching mechanism by its housing, but also for all the connections leading to the apparatus as a whole, no conducting parts being exposed, and one of the housings serving to support the entire structure. 110

115 This application is a division from my application Ser. No. 328,056, filed October 2, 1919, upon which have issued Letters Patent No. 1,480,306.

What I claim is:

1. The combination with a plurality of independent housings, of a base of insulating material separating and secured to them, automatic circuit breaker mechanism within one of said housings upon one side of said base, connecting means extending from said mechanism through said base into another of said housings, said base forming a closure wall of said other of said housings, conduit structure communicating with said other of said housings, and conductors extending through said conduit structure into said housing for effecting electrical communication with said connecting means. 120

2. The combination with a plurality of 125

- 5 housings, of a base of insulating material constituting a wall separating and common to them, one of said housings carrying said base and another of said housings carried by said base, automatic circuit breaker mechanism within said other of said housings carried upon one side of said base, connecting means extending from said mechanism through said base into said one 70 of said housings, and conductors extending into said one of said housings for effecting electrical communication with said connecting means.
- 10 3. The combination with a plurality of 15 housings, of a base common to and secured to them, automatic circuit breaker mechanism within one of said housings upon one side of said base, connecting means extending from said switching mechanism through 20 said base into another of said housings, conduit structure communicating with said other of said housings, conductors extending through said conduit structure into said housing for effecting electrical communication 25 with said connecting means, and means carried by a wall of said one of said housings operable from the exterior thereof for actuating said mechanism.
4. The combination with a plurality of 30 housings, of a base common to them, one of said housings carrying said base and another of said housings carried by said base, automatic circuit breaker mechanism within said other of said housings carried upon one side 35 of said base, connecting means extending from said mechanism through said base into said one of said housings, conductors extending into said one of said housings for effecting electrical communication with said 40 connecting means, and means carried by said other of said housings and operable from the exterior thereof for actuating said mechanism.
5. The combination with a plurality of 45 housings disposed side by side, of a base of insulating material constituting a closure wall common to said housings and separating them, automatic circuit breaker mechanism in one of said housings on one side of 50 said base, studs from said switching mechanism extending through said base into the other of said housings, conduit structure communicating with said other of said housings, conductors in said conduit structure 55 for effecting electrical connection with said studs, and means securing said other of said housings to a support, said base and said one of said housings carried by said other of said housings.
6. The combination with a plurality of 60 housings disposed side by side, of a base of insulating material disposed in vertical position and constituting a wall common to and closing said housings and separating them 65 from each other, means for securing one of said housings to a support, said base secured to said one of said housings independently of said securing means, another of said housings secured to said base, automatic circuit breaker mechanism in said other of said 70 housings secured upon said base, studs extending from said mechanism through said base into one of said housings, conduit structure communicating with said one of said housings, and conductors in said conduits 75 extending free of said one of said housings to said studs.
7. The combination with a plurality of 80 housings, of a base forming a wall common to them, circuit breaker mechanism within one of said housings upon one side of said base, connecting means extending from said mechanism through said base into another of said housings, conductors extending from the exterior into said other of said housings 85 for effecting electrical communication with said connecting means, a hinged door forming a wall of said one of said housings, and means carried by said door for resetting said circuit breaker mechanism. 90
8. The combination with a plurality of 95 housings, of a base of insulating material constituting a closure wall common to said housings and separating them, switching mechanism in one of said housings on one side of said base, connections from said switching mechanism through said base into another of said housings, conductors extending from the exterior into said other of said 100 housings for effecting electrical communication with said connections, said one of said housings having a pivoted door, means carried by and movable with said door for actuating said switching mechanism, and means securing said other of said 105 housings to a support, said base and said one of said housings carried by said other of said housings.
9. An electrical protective unit comprising a base member, automatic circuit breaker 110 mechanism secured to one side of said base member, a housing enclosing said mechanism and secured to said base member, conductors extending from said mechanism through said base member, a second housing 115 secured to the other side of said base member, and conductors extending from the exterior into said second housing for effecting electrical communication with said first named conductors. 120
10. An electrical protective unit comprising a base member, automatic circuit breaker mechanism secured to one side of said base member, a housing enclosing said mechanism and secured to said base member, conductors extending from said mechanism through said base member, a second housing 125 secured to the other side of said base member and adapted to receive conductors for effecting electrical communication with said 130

first named conductors, and means for attaching said second of said housings to a support.

11. An electrical protective unit comprising a pair of housings, a base of insulating material forming a common wall of said housings, automatic circuit breaker mechanism secured upon said base in one of said housings and accessible without entry into the other of said housings, connectors extending from said circuit breaker mechanism through said base into said other of said housings, conductors extending from the exterior into said other of said housings, to effect electrical communication with said connectors, and means for attaching said other of said housings to a support for supporting the unit.
12. An electrical protective unit comprising

ing a base of insulating material, a pair of 20 housings for which said base is a common wall, said base extending to the exterior of said housings, automatic switch mechanism secured to said base within one of said housings and controllable from the exterior of 25 said one of said housings, connectors extending from said circuit breaker mechanism through said base into the other of said housings, said connectors supported by said base and terminating short of the wall of 30 said other of said housings opposite to said base, and conductors extending from the exterior into said other of said housings to said connectors.

In testimony whereof I have hereunto 35 affixed my signature this 21st day of May, 1920.

WILLIAM M. SCOTT.
